LEO M. KOHN, OF BUFFALO, NEW YORK.

FABRIC-FOLDING MACHINE.

1,272,462.

Specification of Letters Patent. Patented July 16, 1918.

Application filed October 25, 1916. Serial No. 127,726.

To all whom it may concern:

Be it known that I, LEO M. KOHN, a citizen of the United States, residing at Buffalo, in the county of Erie and State of New York, have invented new and useful Improvements in Fabric-Folding Machines, of which the following is a specification.

This invention relates to a machine designed more particularly for folding towels, napkins and other short pieces of fabric which will not make a very thick pile, although the same may be adapted for folding other sheet materials.

The object of this invention is to provide a machine of this character which is efficient and reliable in operation and which is capable of folding towels and similar articles of varying lengths neatly, compactly and uniformly and to accomplish this by means which automatically control the operation of the machine.

In the accompanying drawings:

Figure 1 is a side elevation of the machine, showing the parts in operative position. Fig. 2 is a top plan view thereof, partly broken away. Fig. 3 is a central longitudinal section of the same, partly diagrammatic. Fig. 4 is a transverse vertical section taken on line 4—4, Fig. 3. Fig. 5 is an enlarged fragmentary sectional view of the means for raising the supporting table. Fig. 6 is a transverse vertical section taken on line 6—6, Fig. 5. Fig. 7 is a sectional elevation of the means for automatically producing an air gripping effect on the supporting table. Fig. 8 is a view of a towel or other article partially folded.

Similar characters of reference indicate corresponding parts throughout the several views.

In its general organization this machine comprises means for feeding the towels or similar articles which are to be folded, means for folding and pressing said towels, means for automatically rendering said folding and pressing devices operative or inoperative depending on whether or not towels are being supplied to the folding and pressing means, and a delivery mechanism which automatically carries away the towels after the same have been folded and pressed.

1 indicates the main frame which supports the working parts of the machine and which is so designed that the necessary bearings

are provided in the same for supporting the various shafts and other parts.

Journalized in bearings on the frame of the machine are the transverse shafts 2, 3 which carry the feed rollers 4 and 5, respectively, which feed the article to be folded to the machine. The roller 4 is preferably constructed of iron or other material capable of conducting electricity, while the roller 5 is made of wood or other similar material incapable of conducting an electric current, the purpose of which will be hereinafter described. These feed rollers are driven at the same speed in opposite directions from the main driving shaft 6, which is journalized in bearings in the lower portion of the frame, through the medium of a chain belt 7 passing around sprocket wheels 8, 9, mounted on said driving shaft and driven shaft 2, respectively. The roller 5 is turned in a direction opposite to that of the roller 4 by intermeshing spur gears 10, 11 mounted on the respective shafts of said rollers.

Arranged below the feed rollers and at a distance therefrom are two horizontally movable tables 12, 12 arranged side by side but separated from each other, the same being adapted to support the article to be folded. These tables are preferably rectangular and hollow in cross section and each is guided on horizontal tracks or guide rails 13 which extend lengthwise of the machine and are capable of independent vertical movement within a limited range. As shown in the drawings, there are two rails for each table, so located as to support the opposite sides thereof. The rails of each are supported at their front and rear ends by means of parallel links 14, the upper ends of the front links being pivotally connected to a cross rod 15 passing through said rails and the lower ends being pivotally connected to a cross rod 16 supported in the lower portion of the frame, while the rear links are pivotally connected at their upper ends to a cross rod 17 passing through the rear portion of the rails and the lower ends are pivotally connected to a cross rod or shaft 18 journalized in suitable bearings in the lower portion of the frame. By this construction, each pair of rails and the table mounted thereon are adapted to move vertically but are always held horizontally. The extent of the rising and falling movement of each

table is preferably limited by means of upper and lower stops 14^a, 14^b mounted on the main frame in position to be engaged by the links 14 at the upper and lower ends of 5 their predetermined swinging movement.

The tables 12, 12 besides being vertically movable toward and from the feed rollers are also provided with means for reciprocating them on the guide rails lengthwise of 10 the machine. This is accomplished by means of crank arms 19 mounted on the opposite ends of a transverse shaft 20, and connecting rods 21 each of which connects the outer free end of one crank arm to the outer side of 15 the respective table. To vary the width of the plies or folds of the towel means are provided to shorten or lengthen the stroke of each table. This is preferably effected by providing each arm 19 with a longitudinal 20 slot 22 in which a pin 23 on the adjacent end of the connecting rod is adjustably fastened. The shaft 20 is rotated from the main drive shaft 6 by a belt 24 passing around the cone pulleys 25, 26 mounted respectively on the shafts 20 and 6, thereby permitting change of speed when desired. By this arrangement of the drive mechanism, the feed rollers are driven at a constant speed while the reciprocating motion 25 of the tables may be changed to suit the character of the work which is being done.

Rotatably mounted directly above the horizontal tables 12, 12, are two horizontal creasing or molding and pressing rollers 35 27, 28 arranged transversely of the table and on opposite sides of the feed rollers but preferably spaced therefrom. These folding rollers are mounted on transverse shafts 29, 30 suitably journaled in bearings 31, 32 on the 40 frame of the machine and are rotated only when the tables are in their upper or operating positions, at which time the rollers are adapted to engage the upper surfaces of said tables while they are reciprocated 45 lengthwise of the machine. The bearings 31, 32 are preferably slotted, as shown at 33 in Figs. 1 and 3 to permit the folding rollers to rise and fall to a limited extent and thereby accommodate themselves to various thicknesses of material being folded 50 by this machine. This is particularly desirable when folding moist or wet goods which make a higher pile than dry goods of the same thickness. Any suitable means may be 55 employed for causing the rollers to positively rotate during the reciprocation of the tables, but the construction shown in the drawings is preferred and consists of spur gears 34 mounted on the folding roller shafts which 60 are adapted to mesh with gear racks 35 fastened horizontally to the outer side of said tables and thereby cause rotation of these rollers when a table and its gear rack are in their upper or operative position.

65 Means are provided for automatically op-

erating the raising of each towel supporting table 12 independently of the other when a towel enters one section of the machine preparatory to being folded and pressed and for lowering the same when the folding operation has been completed. The preferred means for accomplishing this purpose is 70 that shown in the drawings and is constructed as follows:

36 indicates an air cylinder arranged at an 75 angle to the tables and provided with a rearwardly extending lug or ear 37 which is pivotally mounted on the transverse shaft 18 so as to be capable of swinging freely about the axis of this shaft during the raising and 80 lowering of the tables. Arranged to be operated in this cylinder is a piston 38 having a connecting rod 39 whose free forward end is loosely mounted or pivoted on the cross rod 15. Bolted or otherwise secured to the 85 wall of the cylinder is a valve casing 40 containing a rotary sleeve 41 provided with a transfer port 41^a adapted to register either with a compressed air supply or inlet port 42 or an exhaust port 46 in the casing and 90 also provided with an inlet port 41^b and an outlet port 41^c either of which are adapted to register with a transfer port 43 leading to the air space in the cylinder, as shown in Figs. 5 and 6. The air inlet 42 is connected 95 to the outlet of a rotary centrifugal air pump 44 or other source of supply by a flexible hose 45.

Upon turning the valve sleeve 41 in one 100 direction its transfer port 41^a registers with the inlet port 42 and its outlet port 41^b registers with the transfer port 43 while the ports 46 and 41^c are closed, as shown in Figs. 5 and 6, in which position of the parts compressed air is supplied to the cylinder 36 and 105 the piston 38 therein is pushed outwardly so that the respective folding table is raised into its operative position, as shown by full lines 110 in Figs. 1, 3 and 4. Upon turning the valve sleeve 41 in the opposite direction its transfer port 41^a registers with the exhaust port 46 and its exhaust or outlet port 41^c registers with the transfer port 43 of the valve casing 115 while the ports 42 and 41^b are closed, thereby cutting off the compressed air supply from the cylinder 36 but placing the same in communication with the outer atmosphere whereby the folding table is permitted to drop by 120 its own weight into its lowered or inoperative position. The shifting of the valve 41 is controlled by an electro-magnet or solenoid 47 mounted on or adjacent to the cylinder 36 but having its axis in a plane at right angles to the axis of the valve 41, so as to cause the latter to rotate by the magnetic attraction of the armature of said solenoid motor as will presently be described. Arranged to move vertically within this 125 electro-magnet is an armature 48 normally held upward or out of engagement with the 130

magnet core 49 by means of a spring 50 arranged in a recess or socket 51 in the lower end of said armature and interposed between a projection 52 on said magnet core 49 and the bottom of the socket 51, as shown in Fig. 5. A lever or arm 53 is rigidly secured at one end to a stem 54 on the valve 41 while its other end is loosely connected with the top of the armature 48 by means of a pin 55 and slot 56 to cause the actuation of the valve by the attraction and repulsion of the armature of the solenoid.

For the purpose of operating the electro-magnet which in turn controls the regulation 15 of the valve for raising and lowering the tables, electrical contact is established between the feed rollers 4, 5, by providing each section of the roller 5, which, as hereinbefore described, is made of a non-conducting 20 material, with a contact ring or band 5^a which is so located as to be in the path of the towels which are being fed between said rollers on that particular side or section of the machine and thereby break the contact 25 between them. A brush 57 connected with one terminal of a battery 58 is adapted to make contact with one of the contact rings 5^a and when the feed rollers are electrically connected, that is, when no towel is being 30 passed between them, the current passes from the said contact ring to the roller 4, thence through the shaft 2 and out through the lead wire 59 to a relay solenoid 60 which now becomes energized. At the moment this solenoid 35 becomes energized, it attracts an armature 61 which is preferably in the form of a flat spring with one end fastened to a box-shaped support 62 or other suitable housing for concealing the same. This attraction of 40 the armature by the solenoid 60 opens a switch of which the armature 61 and a contact 45 63 form parts, the latter being arranged in the branch circuit 64 between said armature and the electro-magnet 47 which is associated with the cylinder valve, and thereby preventing current flowing to said magnet. This deenergizing of the valve controlling 50 magnet 47 causes the vertical armature therein to be raised by its spring and hence operates the lever 53 to rotate the valve so as to register with the exhaust passage, and allow the air in the cylinder to escape and lower the piston together with the respective guide rails and table out of engagement with the 55 periphery of the folding rollers 27, 28. When a towel is fed between a contact ring 5^a and the opposing feed roller 4, the circuit between the latter and the respective contact ring is broken, stopping the flow of current 60 to the solenoid 60 which releases the armature and causes it to make contact at 63. This completes the circuit in the branch circuit 64, the current flowing from the battery 65 through the valve controlling magnet 47, 65 the branch 64, contact 63, armature 61, and

back to the battery. At the instant the electro-magnet 47 becomes energized the armature 48 is attracted, overcoming the resistance of the spring 50, and causing the valve 41 to rotate through the medium of the lever 53 to open the valve and thus allow the compressed air to enter the cylinder and raise the piston together with the respective guide rails and table into peripheral engagement with the folding rollers, which properly fold 75 or crease the towel or other article as the table is reciprocated under these rollers.

While the table is thus reciprocating in its elevated position and a towel is being fed downwardly by the feed rollers 4, 5 and upon 80 the table between the folding rollers 27, 28 the towel 28^a is carried alternately in opposite directions in the form of a succession of loops or folds of serpentine form the plies of which are superposed, as shown in Fig. 8. 85 The number of plies vary according to the length of the towel and all the plies are of equal length excepting the first and last ones which may vary according to the length of the towel and the timing of the table raising 90 and lowering mechanism, but in no case are the end plies of the towel wider than the intermediate plies of the same. While the several plies of the towel are being thus laid successively one on top of another the 95 same are pressed so that the same are smooth and free from wrinkles and the turns between the plies are also well set, this being due to the table pressing the towel upwardly against the folding rollers. As the thickness of the folded towel varies the folding rollers are free to rise in the slotted bearings 100 31, 32 in order to adapt themselves to this variation in thickness and produce uniform work.

In order to retain the towels or other sheet fabric materials firmly and smoothly upon each table while being folded the latter is made hollow to form an air exhaust chamber 66^a and provided in its top surface with 110 a series of perforations 66 which communicate with the hollow interior of the table, as shown in Figs. 3 and 4. During the folding operation, the air is withdrawn from the respective table by suction or vacuum pressure which subsequently tends to cause the towels to be drawn or adhere closely and firmly to the top surface of each table and hold them until the folding operation has been completed, at which time the air suction is automatically shut off, by means similar to that employed for raising and lowering the tables. This mechanism for controlling the suction grip of the tables may be 115 constructed as follows:

Connected in series with the circuit 64, in which the battery 65 is interposed, is an electromagnet 67, the construction of which is the same as the magnet 47, hence a detailed description of the same is unnecessary. 120

sary. This magnet is adapted to control a sleeve or rotary valve 68 having an inlet port 68^a and two outlet ports 68^b, 68^c and arranged in a casing 69 which is provided with 5 a suction inlet port or passage 71, a suction outlet port or passage 70, and a vent port 76,—the port 71 communicating with the hollow tables by a flexible tubular connection 72, while the outlet port 70 communicates with a suction pump 73. As in the 10 previously described construction, the armature 74 of the electro-magnet 67 is operatively connected to the valve 68 by means of an arm or lever 75. When the valve 68 is turned in one direction so that its inlet port 68^a registers with the casing port 71, its port 68^b registers with the port 70 and the ports 68^c and 76 are closed, as shown in Fig. 7, then the suction of the pump is connected 15 with the hollow table and the towels are held on the upper side of the latter by a pneumatic grip while being folded and pressed. When the valve is turned in the opposite direction so as to close the ports 68^a and 71 and bring the port 68^b into register with the port 76 and the port 68^c into register with the port 70 then communication with the table is shut off and the air is drawn through a vent port 76 in the valve 20 casing and thence through the ports 68^a, 70, into the suction pump 73. This valve is operated simultaneously with the opening and closing of the valve 41 which controls the raising and lowering of the respective table, 25 because when the table is raised to operative position, an article to be folded is in the machine and it is necessary therefore to have suction at the same time to retain this article firmly on the table while being folded. 30 To produce this simultaneous action for operating the movement of the table and regulating the suction thereto, both magnets are connected in series with each other, as shown in Fig. 3.

40 After the folding operation is completed, the folded article is automatically carried away by means which preferably comprise endless tape carriers 77 and delivered to a suitable receptacle provided for this purpose. These tapes pass over an upper front roller 78, and a lower intermediate roller 79, mounted on shafts 80, 81, and around a rear upper roller 82 mounted on a shaft 83, all of 45 said shafts being suitably journaled in bearings on the frame. Said tapes are constantly in motion and are driven from the main drive shaft 6 by a chain belt 84 passing around sprocket wheels 86, 85 fastened to the shaft 6 and shafts 78, respectively. Each 50 table 12 is provided with a plurality of recesses or grooves 87 extending lengthwise of the same and arranged for the purpose of allowing the tapes 77 to pass freely through the same and lie below the top surface of 55 the table, when the latter is raised in con-

tact with the pressing rollers and in the act of folding a towel. When the table is lowered after the folding operation is completed, the top surface of each table falls below the upper operative stretches of the 70 tapes, and allows the towels to be carried away by them and deposited elsewhere for packing and shipping but when the table is raised the towel being folded is held up out of reach of the tapes, as shown in Figs. 75 3 and 4.

A suitable guiding board or feed table 88 extending transversely of the machine may be arranged above the feed rollers and inclined thereto to properly feed the towels or 80 other fabric materials to said rollers,—as shown in the drawings, this board being supported by brackets 89.

The operation of the machine is as follows:

The towels or other sheet-like articles to be folded by this improved machine are taken from the ironing machine, which is located adjacent to the folding machine and they are deposited on the inclined board 88 90 which guides the same between the feed rollers 4, 5. As is obvious from the drawings, this machine is designed to fold two sets of towels at one time, irrespective of their lengths. In the normal position of 95 the parts of the machine, each table is down and out of contact with the pressing or folding rollers 27, 28, the companion piston 38 is at the lower end of its downward stroke and the armatures of the respective magnets 100 105 are in their uppermost or retracted position so that both valves associated therewith are closed. The moment the towel enters between the two opposing feed rollers it causes the electrical contact between them to be broken, and this in turn causes the circuit, in which the air pressure controlling magnet 47 and the suction controlling magnet 67 are located to be closed, thereby opening the 110 respective valves operated by said electro-motors for supplying the necessary air to the cylinder 36 for raising this table and for producing suction therein. While the towel is between the feed rollers, the table is constantly held in engagement with the periphery of the folding rollers and is reciprocated by the respective crank 19. As the 115 towel is fed down between the rollers, the table travels at such a speed as to take up the slack of the towel delivered from these 120 rollers. When the first stretch of each towel reaches the table, it is held firmly thereto by the air suction and is carried with said table to the end of its stroke. Near the end of each minimum stroke of the table, the 125 towel is so located, that the lower end portion thereof rests horizontally on the table and the adjacent or intermediate portion thereof hangs vertically from the feed rollers ready to be folded upon the preceding 130

horizontal portion by passing under either of the folding rollers when the table completes the end of its stroke. During this time, the upper end portion of the towel is 5 being fed between the rollers and is folded upon the intermediate portion of the towel at the opposite end of the previous ply or fold on the return stroke of the table by passing under the other folding roller. It 10 is thus seen that the towel is folded upon itself at both ends in substantially flattened serpentine form, as illustrated in Fig. 8. When the end portions of the towel escape from the feed rollers to the table, electrical 15 contact is made between the roller 4 and the respective metal ring 5^a which completes the circuit through the companion solenoid 60 and breaks the contact at 63 by reason of the armature 61 being attracted by said 20 solenoid. This causes a break in the circuit in which the respective electro-magnets 47 and 67 are included, thus deenergizing the same and releasing the respective armatures which close the valves operated thereby, 25 shutting off the vacuum supply to the respective table and the compressed air to the cylinder 36. When the air supply to the cylinder is shut off, the valve 41 allows the air in the cylinder to escape to the atmosphere, 30 and permit this table to lower out of engagement with the folding rollers. As the table falls and the top surface thereof is arranged below the path of the tapes 77, the folded towels are carried by the latter 35 to the front end of the machine and delivered to a suitable receptacle.

By shortening or lengthening the connection between the cranks 19 and the links leading to the tables and also shifting the 40 belt 24 from one pair of corresponding sections of the cone pulleys to another, the machine can be adapted to fold towels and the like so that the plies thereof are of varying width to suit requirements. Accordingly 45 when a comparatively wide fold is desired the connection between the links 21 and the cranks 19 is carried farther away from the shaft 20 and the speed of the latter is reduced in order to give the feed mechanism 50 ample time to supply the desired length of material, but when narrower folds are desired the connection between the cranks and the links is carried nearer to the shaft 20 and the speed of the latter is increased, so 55 that the movement of the folding table keeps pace with the feeding rolls.

This improved machine is very efficient and rapid in operation and, being automatic, requires no additional expense for attendants. Furthermore, the towels, no matter 60 what their length, are all folded to a uniform form size, thereby facilitating the packing thereof.

The towels are fed to and folded in two 65 separate and distinct sets between the fold-

ing rollers and the two folding tables, so that, in effect, this machine is doubled, and during the operation of the machine each table rises and falls independently of the other so that either long or short towels 70 may be fed indiscriminately to both sections of the machine without one interfering with the other, thereby materially facilitating the folding operation and obtaining the maximum output of the machine. 75

I claim as my invention:

1. A sheet fabric folding machine comprising a folding roller, a folding table having a reciprocating movement past said roller and coöperating with the latter for 80 folding a sheet of fabric between the same and means which control the operative relation of said roller and table and which are responsive to the absence and presence of a sheet moving into the machine. 85

2. A sheet fabric folding machine comprising a folding roller, a folding table having a reciprocating movement past said roller and coöperating with the latter for 90 folding a sheet of fabric between the same and said roller and table being also movable one toward and from the other for gripping and releasing the article operated on and means which control the operative relation of said roller and table and which are 95 responsive to the absence and presence of a sheet moving into the machine.

3. A sheet fabric folding machine comprising a pair of folding rollers arranged side by side, a folding table coöperating 100 with said rollers for folding a sheet of fabric between the same, means for reciprocating said table relatively to said rollers and means which control the operative relation of said roller and table and which are responsive to the absence and presence of a sheet moving into the machine. 105

4. A sheet fabric folding machine comprising a pair of folding rollers arranged side by side, a folding table coöperating 110 with said rollers for folding a sheet of fabric between the same, means for reciprocating said table relatively to said rollers, means for moving said table toward and from said rollers and means which control the operative relation of said roller and table and which are responsive to the absence and presence of a sheet moving into the machine. 115

5. A sheet fabric folding machine comprising a pair of folding rollers arranged side by side, a reciprocating folding table coöperating with said rollers for folding a sheet of fabric between the same, means for reciprocating said table relatively to said 120 rollers, and means for carrying the folded article away from said rollers and table. 125

6. A sheet fabric folding machine comprising a pair of folding rollers arranged side by side, a reciprocating folding table 130

- coöperating with said rollers for folding a sheet of fabric between the same, means for reciprocating said table relatively to said rollers, means for moving said table toward and from said rollers, and means for automatically carrying away the folded article from said rollers and table when said table is moved away from said rollers.
7. A sheet fabric folding machine comprising a pair of folding rollers arranged side by side, a reciprocating folding table coöperating with said rollers for folding a sheet of fabric between the same, means for reciprocating said table relatively to said rollers, and electrically controlled means for moving said table toward and from said rollers.
8. A sheet fabric folding machine comprising a pair of folding rollers arranged side by side, a reciprocating folding table coöperating with said rollers for folding a sheet of fabric between the same, means for reciprocating said table relatively to said rollers, shifting means for moving said table toward and from said rollers, and an electric device which controls the operation of said shifting means and the circuit of which is opened and closed by the presence and absence of a sheet of fabric between said rollers.
9. A sheet fabric folding machine comprising a pair of folding rollers arranged side by side, a reciprocating folding table coöperating with said rollers for folding a sheet of fabric between the same, means for reciprocating said table relatively to said rollers, means for moving said table toward and from said rollers, means for feeding the article to be folded to said table between said folding rollers and means which control the operative relation of said rollers and table and which are responsive to the absence and presence of a sheet moving into the machine.
10. A sheet fabric folding machine comprising a pair of folding rollers arranged side by side, a reciprocating folding table coöperating with said rollers for folding a sheet of fabric between the same, means for reciprocating said table relatively to said rollers, means for moving said table toward and from said rollers, a pair of feed rollers for feeding the article to be folded to said table between said folding rollers and means which control the operative relation of said rollers and table and which are responsive to the absence and presence of a sheet moving into the machine.
11. In a machine for folding towels and the like, the combination of feeding rollers, a table movable relatively to said rollers, folding rollers arranged adjacent to said table and movable thereby, and means for automatically raising and lowering said table toward and from said folding rollers which

are responsive to the absence and presence of a sheet moving into the machine.

12. In a machine for folding towels and the like, the combination of feeding rollers, a reciprocating table, means for horizontally guiding said table, folding rollers arranged adjacent to the latter and adapted to be rotated by the movement of the table, and means for automatically raising and lowering said table toward and from said folding rollers which are responsive to the absence and presence of a sheet moving into the machine.

13. In a machine for folding towels and the like, the combination of feeding rollers, a reciprocating table for supporting the article to be folded, means for horizontally guiding said table, folding rollers arranged above the latter and adapted to be rotated by the reciprocation of the table, and electro-magnetically controlled mechanism for raising and lowering said table toward and from said folding rollers.

14. In a machine for folding towels and the like, the combination of feeding rollers adapted to make electrical contact with each other, a reciprocating table for supporting the article to be folded, means for horizontally guiding said table, folding rollers arranged above the latter and adapted to be rotated by the reciprocation of the table, an electric circuit including said feeding rollers and electro-magnetically controlled mechanism for raising and lowering said table toward and from said folding rollers when a towel is passing between said feeding rollers.

15. In a machine for folding towels and the like, the combination of feeding rollers having means adapted to make electrical contact with each other, a reciprocating table for supporting the article to be folded, means for horizontally guiding said table, folding rollers arranged above the latter, means for raising and lowering said table toward and from said folding rollers, and coöperating means arranged on said table and said rollers when said table is in its raised position for effecting rotation of said rollers.

16. In a machine for folding towels and the like, the combination of feeding rollers adapted to make electrical contact with each other, a reciprocating table for supporting the article to be folded, means for horizontally guiding said table, folding rollers arranged above the latter and adapted to engage said table for folding the article, and electro-magnetically controlled mechanism arranged in circuit with said feeding rollers for raising said table into operative relation to said folding rollers when a towel is passing between the feeding rollers, said towel acting as a circuit breaker therefor.

17. In a machine for folding towels and the like, the combination of feeding rollers

adapted to make electrical contact with each other, a reciprocating table for supporting the article to be folded, means for horizontally guiding said table, folding rollers arranged above the latter and adapted to be rotated by the reciprocation of the table, electro-magnetically controlled mechanism for raising and lowering said table into and out of operative relation to said folding rollers, and means for carrying the folded article away after said table is lowered.

18. In a machine for folding towels and the like, the combination of feeding rollers, a reciprocating table for supporting the article to be folded and provided with a plurality of grooves, means for horizontally guiding said table, folding rollers arranged above the latter, means for raising and lowering said table into and out of operative relation to said folding rollers, and means for carrying the folded article away comprising endless tapes adapted to pass through the grooves in said table when the same is in its raised position and to pass above the upper surface of the table when the latter is in its lowered position.

19. In a machine for folding towels and the like, the combination of feeding rollers, a hollow table provided with perforations in its top and movable relatively to said rollers, folding rollers arranged adjacent to the latter and adapted to be rotated by the movement of the table, and means for producing suction in said table.

20. In a machine for folding towels and the like, the combination of feeding rollers adapted to make electrical contact with each other, a hollow table provided with perforations in its top for supporting the article to be folded and movable relatively to said rollers, folding rollers arranged above said table, and electro-magnetically controlled mechanism included in a circuit with said feeding rollers for producing a vacuum in said table when the same is in its raised position.

21. In a machine for folding towels and the like, the combination of feeding rollers, a hollow reciprocating table provided with perforations in its top surface for supporting the article to be folded, folding rollers arranged above said table and electro-magnetically controlled mechanism for producing a vacuum in said table when a towel is passing between said feeding rollers.

22. In a machine for folding towels and the like, the combination of feeding rollers, a hollow reciprocating table provided with perforations in its top surface for supporting the article to be folded, folding rollers arranged above said table, and electrically controlled means for raising the table into engagement with said folding rollers and for producing a vacuum in the table when a towel is passing between said feeding rollers.

23. In a machine for folding towels and the like, the combination of feeding rollers, a hollow reciprocating table provided with perforations in its top for supporting the article to be folded, folding rollers arranged above said table, and electro-magnetically controlled mechanisms for raising the table into engagement with said folding rollers and for producing a vacuum in the table when a towel is passing between said feeding rollers, said mechanisms being capable of operation simultaneously.

24. In a machine for folding towels and the like, the combination of feeding rollers, a reciprocating table for supporting the article to be folded, folding rollers arranged above said table, and means for raising and lowering said table into and out of engagement with said folding rollers comprising a cylinder, a piston movable in said cylinder and co-operating with said table and an electro-magnetically controlled valve for regulating the admission of air to said cylinder.

25. In a machine for folding towels and the like, the combination of feeding rollers, a reciprocating table for supporting the article to be folded, folding rollers arranged above said table, and means for raising the table into engagement with said folding rollers when a towel is passing between the feeding rollers comprising a cylinder, a piston movable therein and co-operating with said table, a valve for regulating the admission of air to said cylinder, and an electro-motor adapted to control the opening and closing of said valve.

26. In a machine for folding towels and the like, the combination of feeding rollers, a reciprocating table for supporting the article to be folded, folding rollers arranged above said table, and means for raising the table into engagement with said folding rollers comprising a cylinder, a piston movable therein and co-operating with said table, a rotatable valve for controlling the admission of air to said cylinder for raising the table, two electro-motors, one of which is adapted to operate the other for controlling the opening of said valve when a towel is passing between the feeding rollers, said towel acting as a circuit breaker.

27. In a machine for folding towels and the like, the combination of feeding rollers, a hollow reciprocating table provided with perforations in its top for supporting the article to be folded, folding rollers arranged above the table, and means for producing a vacuum in said table for retaining the towels thereto comprising an electro-magnetically controlled valve for regulating the vacuum in said table.

28. In a machine for folding towels and the like, the combination of feeding rollers, a hollow reciprocating table provided with

- perforations in its top for supporting the article to be folded, folding rollers arranged above the table, and means for producing a vacuum in said table for retaining the towels 5 thereto when a towel is passing between the feeding rollers comprising a vacuum pump connected with the interior of said table, a valve for regulating the vacuum in said table, and an electro-magnet adapted to 10 control the opening and closing of said valve.
29. In a machine for folding towels and the like, the combination of feeding rollers, a hollow reciprocating table provided with 15 perforations in its top for supporting the article to be folded, folding rollers arranged above said table, and means for simultaneously raising the table into engagement with said folding rollers and for producing a 20 vacuum therein when a towel is between said feeding rollers, comprising air suction and compression devices, including a cylinder, a piston movable in said cylinder and co-operating with the latter to raise said table, a 25 valve for regulating the admission of air to said cylinder, a valve for regulating the vacuum in the table, and electro-magnets for controlling the opening and closing of said valve.
30. A sheet fabric folding machine comprising folding rollers, a folding table reciprocating relatively to said rollers, a shaft provided with a crank, a link connecting said crank with said table, and means which 35 control the operative relation of said rollers and feed table and which are responsive to the absence and presence of a sheet moving into the machine.
31. A sheet fabric folding machine comprising folding rollers, a folding table reciprocating relatively to said rollers, a shaft provided with a crank, a link connecting said crank with said table, means for adjustably connecting the other end of said link with 40 said crank, and means which control the operative relation of said rollers and feed table and which are responsive to the absence and presence of a sheet moving into the machine.
32. A sheet fabric folding machine comprising folding rollers, a folding table reciprocating relatively to said rollers, a shaft provided with a crank, a link connecting said crank with said table, means for adjustably connecting the other end of said link with 45 said crank, means for changing the speed of said shaft, and means which control the operative relation of said rollers and feed table and which are responsive to the absence and presence of a sheet moving into the machine.
33. A sheet fabric folding machine comprising folding rollers, a reciprocating folding table movable toward and from said rollers, movable tracks on which said table slides, a main frame, and links connecting said frame with said tracks.
34. A sheet fabric folding machine comprising folding rollers, a reciprocating folding table movable toward and from said rollers, movable tracks on which said table slides, a main frame, and links connecting said frame with said slides, and stops for limiting the swinging movement of said tracks.
35. A sheet fabric folding machine comprising folding rollers, a reciprocating folding table movable toward and from said rollers, gear wheels arranged on said rollers, a gear rack arranged on said table and 50 movable into and out of engagement with said gear wheels, and means which control the operative relation of said rollers and feed table and which are responsive to the absence and presence of a sheet moving into the machine.

LEO M. KOHN.
